(57) **CLAIM**

The ornamental design for the key matrix for a handset, as
shown.

DESCRIPTION

FIG. 1 is a left side view of the key matrix for a handset;
FIG. 2 is a front view thereof;
FIG. 3 is a right side view thereof;
FIG. 4 is a perspective front view thereof; and,
FIG. 5 is a perspective rear view thereof.
The portions of the drawings shown in broken lines are for
illustrative purposes only and form no part of the claimed
design.
